CLAIM

The ornamental design for a toilet as shown and described.

DESCRIPTION

FIG. 1 is a perspective view of a toilet according to the first embodiment, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a perspective view of a toilet according to the second embodiment, showing our new design;

FIG. 8 is a front view thereof;

FIG. 9 is a rear view thereof;

FIG. 10 is a left side view thereof;

FIG. 11 is a right side view thereof; and,

FIG. 12 is a top view thereof.

The broken lines in the drawings are for the purpose of illustrating portions of the toilet that form no part of the claimed design.
